FACE FOR A TIMEPIECE

George W. Booth, P.O. Box 452,
Greenville, R.I. 02828

Filed Sept. 11, 1967, Ser. No. 8,547

Term of patent 14 years

(Cl. D42—1)

The figure is a top plan view of a face for a timepiece showing my new design, the face being conventionally of no appreciable thickness, the broken line showings of a watch case, hands and portion of a watch bracelet being for illustrative purposes only.

I claim:

The ornamental design for a face for a timepiece, as shown and described.
